UNITED STATES PATENT OFFICE.

JASON C. LOTTERHAND, OF NEW YORK, N. Y., ASSIGNOR TO ADDOMETER CORPORATION,
A CORPORATION OF DELAWARE.

ADDING MECHANISM.

1,102,157.

Specification of Letters Patent. Patented June 30, 1914.

Application filed February 3, 1913. Serial No. 745,892.

To all whom it may concern:

Be it known that I, JASON C. LOTTERHAND, a citizen of the United States, residing in New York, in the county of New York and State of New York, have invented certain new and useful Improvements in Adding Mechanism, of which the following is a specification.

One of the objects of the present invention is to provide an improved form of mechanism in an adding machine, in connection with the adding devices and printing devices of any suitable form connected therewith, whereby the total of the items 10 that have been set up will be caused to print and thereupon the adding devices will be restored to the zero position.

Another object of the invention is to provide an improved form of sub-total device 20 in connection with such a machine whereby the total of the items that have been set up is printed, but instead of the adding devices returning to zero, the total printed is held so that further items can be added to such a 25 total, that is known in the art as a "sub-total."

A further object is to provide in connection with the total and sub-total mechanism, key-operating devices that are simply depressed and held in depressed position by 30 the machine, and do not require to be held down by the fingers of the operator while the main operating member is actuated.

Another object of the invention is to provide an improved form of mechanism in connection with the adding devices, and a suitable printing mechanism connected therewith, whereby on the operation of the 35 actuating member a numeral or item set up on the key-board will be printed in the usual manner, but the adding mechanism will be locked so that the item will not be added to the sum already set up in the adding device.

Another object is to provide means in the form of a single member connected with each adding wheel and its coöperating column or bank of key stops, that will serve to lock each rack and type plate in normal 40 position to release the same upon the advance of any of the key-stops; which member will further operate when shifted by a special key-connection to restore any of the key bars that may have been advanced.

Another object of the invention is to pro-

vide an improved form of so called "flexible key-board" whereby when any stop bar connected with a key has been advanced and is found to be not the one desired, the operation of pressing any other key of the 50 same bank will restore the key that was depressed.

Another object of the invention is to provide an improved form of restoring device, 55 that at each operation of the actuating member, will restore all of the keys that have been depressed; and in connection with such mechanism a single key member that will also serve to restore all keys that may have been depressed.

Another object of the invention is to provide means whereby a form of retarding device is provided to regulate the return movement of the main actuating shaft, in connection with a universal bar and the adding 70 mechanism, whereby certain parts of the adding mechanism are moved or restored after the universal bar is brought to rest, and each movement of such parts is controlled by the said retarding device.

In the accompanying drawings, showing one embodiment of my invention, Figure 1 is a side elevation of the machine with the casing and one of the side plates removed; Fig. 2 shows a detail of one stop bar; Fig. 3 is a view showing the arrangement of the stop bars for three banks of keys and connected parts; Fig. 4 is a plan view of the 75 machine with certain parts omitted; Fig. 5 is a view of certain parts on the left side of the machine with the casing removed; Fig. 6 is a fragmentary view of the parts shown in Fig. 5, in different relative positions; Figs. 7 and 8 correspond to Fig. 6, with the parts in different relative positions; Fig. 9 is an end elevation of the total key and connected parts; Fig. 10 is a view of the right side of the machine with the casing removed; Fig. 11 is a fragmentary view of 80 most of the parts shown in Fig. 10; Fig. 12 is a detail view showing one of the latches for the restoring bar; Fig. 13 is a view showing, enlarged, the set of stop plates with the adjacent rack bars coöperating therewith; Fig. 14 is a view of one of the 85 stop plates; Fig. 15 is a section on the line 15-15 of Fig. 13; Fig. 16 is a fragmentary view showing one of the adding pinions and its connected parts; Fig. 17 is a similar view with the parts in other positions; Fig. 18 is 90

a plan view of the parts shown in Fig. 16; Fig. 19 is a front elevation of the parts shown in Fig. 18; Fig. 20 shows one of the segment levers; Fig. 21 shows one of the detent members; and, Fig. 22 is a fragmentary view showing a form of printing mechanism.

In the drawings the machine is shown as mounted on a suitable base 1 that is provided 10 with side plates 2 and 3, supporting considerable of the mechanism and parts. A cover 4 is also shown to inclose all of the parts. At the front of the machine is the usual arrangement of keys forming a key- 15 board, an inclined plate 5 being shown provided with rows of slots 6 through which project the stems 7 of the keys. These are arranged in vertical columns in the usual manner of nine in each column, and in the 20 present machine there are nine rows of such columns or keys extending across the machine.

For each of the columns is a set of stop-bars, that coöperate with a rack and type 25 plate, the latter serving to control an adding pinion. Each key stem 7 is pivoted to a crank 8 swinging on a supporting plate 17. The cranks 8 are each pivoted to a stop bar 9 extending horizontally and sliding in slots 30 11 in a vertical transverse plate 10. It will be observed from Fig. 3 that for each column there are nine of these stop bars having a staggered arrangement, and each one of the nine is vertically offset an equal distance 35 from the adjacent one. When a key is depressed it will swing the crank and advance the stop bar 9 rearwardly, as indicated in Fig. 1. A spring 13 is placed on the end portion of each stop bar 9 engaging by its 40 ends the plate 10 and a cross bar 14 on the bar, respectively, tending to force the stop-bar forward until a lug 15 on the stop bar engages a stop plate 12, similar to the plate 10 which is the normal position of the stop 45 bars. But when the stop bar is moved rearward, the inclined face of the lug 15 will strike a pin 216 on a vertically movable latch-plate 16 and elevate the latch-plate, and after the lug passes the pin the latch 50 plate will drop so that the pin will lie opposite the abutment face of the lug 15. When the key is released by the finger, the spring will force the stop bar forward until this pin strikes the lug 15, as indicated in Fig. 2, 55 that will arrest the stop bar in the advanced position. The latch plate 16 is supported by a link 18 at its lower portion and at its upper portion by a lever 19, and is pulled downwardly by a spring 20 connected with 60 an extension 21 on the latch plate. The latch plate is provided with nine of these pins 216, four on one side and five on the other, positioned to coöperate with the nine stop bars, respectively, each latch plate being interposed between the two rows constituting

tuting each group of stop bars, as indicated in Fig. 3. If any latch bar of a set has been advanced and its lug locked behind the pin, as indicated in Fig. 2, the depression of another key to advance its stop bar will cause the lug on such stop bar to strike the pin and raise the latch bar. This raising of the latch bar will move all of the pins away from the stop bars, and therefore any latch-bar previously advanced will be released 70 from the pin and moved forwardly by the spring 13 thereof. By this means when any key has been depressed in a column and it is desired to have it restored and another key be depressed, it is only necessary to depress 80 the proper key, when the previous key will be restored.

Means are also provided for simultaneously raising all of the latch plates 16, a rod 22 being shown located below the lower end of the latch plates carried on arms 23 and 24, and also connected by a link 25 with a lever 26 that is pivoted at 27 on one of the side plates. When this lever is swung by depressing a key 28, the rod 22 will be elevated, raising all of the latch plates and releasing all of the stop bars that may have been advanced.

Means are further provided for raising the bar 22 to shift all of the latch plates, 95 each time the actuating shaft for the machine is operated to add or print an item set up by the keys. A shaft 60 (see Figs. 1 and 4) extends across the base at the forward part of the machine that is shown as operated by a handle 61. On the shaft 60 is a crank 35 carrying a pin 36. This pin is arranged to coöperate with a latch 29 pivoted on the lever 26 in the normal position of the latch, as indicated in Fig. 1, the pin swinging the latch down as the crank and pin move forward, but on the return stroke the pin striking the latch to swing the lever 26 and raise the bar 22. Connected with the latch 29 is a link 30 arranged to be engaged by a pin 31 on a key stem 32, that is provided with a ledge 33 arranged to engage under the plate 5 when this key is depressed and held in such position by a spring 34. The depression of this key will swing the link 30 to shift the latch to the position indicated in broken lines in Fig. 1, whereby the pin 36 will move freely past the latch and not serve to shift the lever 26. This constitutes the repeat key whereby when any keys have been depressed to set up an item it will remain set up and this number will be added and printed for each successive operation of the handle. But moving the key 32 forward will release its shoulder 125 from the plate and it will be restored by the spring 34, permitting the lever 26 to restore all of the key bars as described.

Means are also provided for locking the keys against any movement after the initial 130

movement of the handle and shaft 60 so that no other keys can be depressed or any changes made in the key board. A bar 37 is mounted to swing on arms 38 mounted in 5 the side plates respectively, (see Fig. 1,) which bar engages the extension 21 of the levers 19 in the position shown, and prevents all of the latch bars from rising. One arm 38 is provided with a cam 40 that engages 10 a pin 39 mounted on a side bar 53 that is pivoted to a crank plate 59 carried by the shaft 60, and hence reciprocating from the handle. (See Fig. 12.) In the normal rearward position of the handle and 15 side plate, the pin lies at the cam portion 40 and the spring 41 will drive the bar 37 forward releasing the latch plates. But at the initial movement of the handle and side bar the cam 40 will swing the arm 38 and cause 20 the rod 37 to engage the latch plates and lock them against being elevated. It will be observed from the shape of the cam that the bar will remain in this position during the entire rearward movement of the side 25 bar and until the final portion of its return movement, so that no change can be made in the keys after the first initial movement of the handle and shaft.

A rack and type plate 42 is arranged one 30 for each of the sets of stop bars, each plate sliding vertically on a post 43 that it engages by guides 44. (See Figs. 1 and 4.) The post 43 is tubular and contains a spring 45 connected with the type plate to draw it 35 upwardly when in the lowermost position. These plates are moved downwardly and normally held in such position by a universal bar 46 that engages a stop 62 at the rear of each rack. The bar 46 is carried by arms 47 and 48 fast on a cross shaft 49 at the 40 rear of the machine having bearings in the side plates 2 and 3.

A crank 50 on one side is fast on the shaft 49 and carries a pin 51 riding in a slot 52 in the side bar 53 so that the crank has a limited movement independent of the side bar. A link 54 is pivoted on pin 51 and pivotally connects to a lever 55 pivoted on the side bar, (see Fig. 10) and provided with 50 an arm 56 projecting upward to engage a stop pin 57 at the latter portion of the rearward movement of the side bar, that will serve to break the alinement of the link members 54 and 55. The shaft 49 carries 55 a crank 171 (see Fig. 4) connecting by one or more springs 170 with a bracket 172 that is held stationary. This spring tends to swing the shaft 49 to move the crank 50 rearward, and when the bar 53 is drawn forward by operating the handle, the pin 51 on the crank 50 will be held stationary, and the links 54 and 55 will straighten out putting the spring 58 under tension, that connects pin 51 with the pivot of link 55. This 60 produces the effect of making the pin 51

practically rigid with the said side bar 53, and the further movement of the shaft 60 will cause the crank 51 to swing forward, rocking the shaft 49 against the tension of the springs 170. When the handle is released or moved rearward again, the side bar 53 will move rearward under the tension of the spring 170. The crank 50 will swing rearward with the link still in its straight position, until the arm 56 strikes the stop pin 57. This will break the toggle link, and the arm 50 is now arrested because of stops 180 and 181 engaging the arms 47 and 48 of the universal bar, which will bring the universal bar to rest in its lowermost position. But the spring 58 on the link that was put under tension when the link became straight, now that the link is broken by the pin 57 will draw the side bar 53 still farther rearward. Certain parts of the mechanism, set forth hereinafter, are operatively connected with the side bars and as the side bar is given an additional movement after the universal bar and shaft 49 come to rest, certain operations are effected after the universal bar is returned to its normal position:

It is customary in this art to provide a retarding means for the return of the handle and main shaft, so that the handle can be drawn forward and released and the retarding device will prevent a too rapid return of the handle and a too rapid operation of the parts operated on the return stroke of the handle. A retarding device in the form of a dash-pot 164 is shown having its plunger 165 secured at the outer end to a cross bar 173. (See Figs. 1 and 4.) The dash pot 164 is carried by a yoke 166 that is pivotally mounted on the shaft 49, but free to swing thereon. An arm 167 extends downward from the yoke 166 and is pivoted to a link 168. The latter is pivoted to a stud 169 fast to the side bar 53. It will thus be seen that this dash pot operates directly on the side bar and not directly on the crank shaft carrying the universal bar; whereby the entire return movement of the side bar is under the control of the retarding device, and the side bar cannot jump back quickly after the universal bar has been brought to rest. The rack and type plates 42 are thus normally held down by the universal bar 46, and when this bar is permitted to rise by the operation of the handle, and the rack and type plates to be carried up by their springs until the stops 63 at the front of each rack and type plate, engage one of the stop bars 9 that has been advanced, as indicated in Fig. 1 this will 115 arrest that particular rack and type plate and the universal bar will rise free therefrom for the remainder of its upward movement. These plates 42 have a rack 73 on their forward edge, with which engage nu- 120

meral pinions 74 when the pinions are shifted into the path of the rack bars. Each rack and type plate 42 has a carrier portion 64 in which are arranged a set of type 5 65 in the form of plungers. The printing mechanism forms no part of the present invention, but a form of such operating mechanism will be described for the sake of clearness, see Fig. 22.

10 A set of type hammers 66 are pivotally mounted and each is swung by a trigger 71 mounted on a shaft 72 connected with the arms 47 and 48. When the trigger moves rearward, its hook 70 engages tips 69 on 15 the lower end of the hammer and swings the hammer rearward. When the trigger releases the hammer it is swung back by an energizer 67 controlled by a spring 68, which energizer engages the rear of the 20 hammer. As the rack and type plate is elevated to nine different positions, according to the nine stop bars, this will bring one of the nine different type 65 to be engaged by the hammer 66 when swung. This 25 will cause the rack and type plate to effect the printing of the numbers as desired from the position of the stop bars. The triggers 71 will serve to operate the hammers at the latter portion of the stroke of the side bar 30 that elevates the universal bar 46, and this will be referred to later in regard to the printing of the totals and the sub-totals, because when a total is printed the adding device is returned to zero, while when a 35 sub-total is printed the adding device is restored to its total that has been printed.

The numeral pinions 74 are mounted free to turn on a shaft 75 extending across the machine and carried by supports in the form 40 of an arm 76 on one side of the machine and a lever 77 on the other side of the machine rocking on a pivot 183. By shifting this shaft 75, the pinions 74 can be shifted from engagement with the rack bars 73, to 45 a position free from the rack bars. When the rack bars 73 are reciprocated a distance governed by the positioned stopbar 9, the pinions 3 in mesh therewith will be rotated a corresponding distance. The pinions are 50 held in engagement with the rack bars during their movement in one direction only in the normal operation of the machine, and by swinging these levers the pinions are moved to disengage the rack bars during 55 their movement in the other direction. In this particular machine, in the normal adding operation, the pinions will be held away from the rack bars, as indicated in Fig. 10, and after the keys have been depressed to 60 position the stop-bars 9, the swinging of the handle and consequent rising of the universal bar 46 will permit the rack bars to rise by their tensioned springs, until the stop 65 on the forward part of the rack bar engages the appropriate positioned stop bar. There-

upon, by means hereinafter set forth, the pinions are all shifted rearwardly to engage the rack bars and hold them engaged during the return movement of the rack bars caused by the return of the universal 70 bar. Thereupon, the pinions will be rotated a distance corresponding with the movement of the rack bars, that is controlled by the stop bars.

Carrying mechanism is provided for each 75 numeral wheel, except the last wheel on the left hand side, whereby as each wheel completes a revolution and begins the second revolution the carrying operation takes place to advance the wheel or pinion of next 80 higher denomination a single number. This mechanism is operative to be set during the rotation of the wheel in engagement with the rack bar, but the carrying operation is not done at such time. At a subsequent 85 stage in the operation, after the pinions are all moved forwardly to disengage the rack bars and the rack bars are returned to normal position by the universal bar, then such set members are caused to effect 90 the carrying operation.

The mechanism for the carrying operation comprises essentially a toothed segment lever and an operating detent lever for each of the pinions. In front of each pinion 95 74 is an elbow lever 93 (see Figs. 16 and 17) that are all mounted on a stationary shaft 80 supported in the side plates. Each elbow lever has a segment arm 79 projecting rearwardly and provided with teeth 100 corresponding with the teeth of the pinions 74, and these segments are positioned so that immediately upon the pinions being swung forward and disengaging the racks 73, they will engage these segments, whereby the pinions are constantly controlled by one of these two members. It will be seen that when the pinions engage the rack bars, the toothed segments are free to swing, as indicated in Fig. 1. But when the pinions 110 are shifted forward, as indicated in Fig. 16, rocking of the elbow lever 93 will turn the pinion 74 the same direction in which it is turned by the downward movement of the rack bar in engagement therewith. Each 115 of the elbow levers has a downwardly extending arm 81 provided with an ear 82 extending to the right toward the pinion of lower denomination. A spring 89 connects each arm 81 with a suitable part of the machine, tending to draw the arm 81 rearwardly to swing the toothed segment upwardly from the position shown in Fig. 17 to that shown in Fig. 16; and if the pinion 120 engages the segment at such time the same will be advanced to effect the carrying operation.

For each of the elbow levers 93 there is a detent lever 94 shown separately in Fig. 21, having an arm 83 projecting forwardly and 130

provided with a catch 184. These levers all swing on a stationary cross shaft 84, and are positioned to have each catch 184 cooperate with the ear 82 on the depending arm 81. A spring 88 connects the arm 83 with a piece 185 connected with the shaft 80, tending to swing the arm 83 upwardly into engagement with the ear 82, thereby causing the ear to engage the catch 184, as indicated 10 in Fig. 17, whereby this catch will prevent rearward movement of the arm 81 by its spring. When the detent 94 is tripped as the arm 83 swings downwardly so that the catch releases the ear, the spring 89 will 15 draw the arm 81 rearward causing the toothed segment to swing the pinion if the latter is shifted forward in engagement therewith.

The detent 94 is provided with an upwardly extending arm 85 provided with a stop 86 at its upper end. It will be observed that the arm and stop 86 is offset to the right a short distance from the pinion corresponding with the toothed segment 25 whose lever and ear engage this detent, that is, coöperate with the pinion of next lower denomination. Each of the pinions 74 is provided with a lug or cam 87, that, when the wheel is swung in the direction of the 30 arrow, will strike the stop 86 to move the arm 85 forwardly and swing the detent arm 83 downwardly, thereby tripping the detent to free the ear 82 of the elbow lever 93. This would permit the toothed segment to 35 swing and if the pinion were in engagement therewith, it would be turned. But the pinions are only rotated when shifted rearwardly to engage the rack bars, as indicated in Fig. 17, in which position of the 40 parts the toothed segment is free from the pinion. It is by this movement of the rack bars that the pinions are rotated causing the cam 87 to swing the detent lever to trip the elbow levers 93. Therefore means are provided 45 for engaging the elbow levers to arrest their free movement and to hold them tripped from the detent arm until in a subsequent stage the pinions 74 have been shifted forwardly, disengaging the rack bars 50 and engaging the segment arms. Thereupon the release of the elbow levers will permit them to be swung by their actuating springs a sufficient distance to turn the pinions a single tooth, to advance them a unit 55 distance. This function is accomplished by a restoring bar 90 carried by arms 91 and 92 swinging on opposite sides of the machine on the side plates.

The bar 90 is normally held a short distance offset from the lower end of the arm 81, whereby when the detent is swung by the cam to release the ear 82, the arm 81 can be swung by its spring a short distance to pass the catch 184 and prevent reengagement when the cam leaves the stop 86 of the

detent. The carrying levers are held in this position by the restoring bar until the pinions are swung forward to engage the segment arms. Then the bar 90 is shifted rearwardly which will permit the elbow levers to be swung by their springs a sufficient distance to turn the pinions a unit distance to carry. It will, of course, be understood that all of the elbow levers and corresponding detents are independent, and only those tripped by the cam 87 will be permitted to swing when the restoring bar moves rearwardly. When the restoring bar 90 is moved forwardly, it will engage the depending arm 81 and swing it forward, thereby permitting the ears 82 to reengage the catch 184 on the arms 83. But the latter operation is not effected until the pinions have been swung rearward free from the segment arms 79.

The means for operating the restoring bar 90 in timed relation to the operation of the universal bar 46, and also for operating the lever 77 to shift the numeral pinions into engagement alternately with the rack bars 90 and with the segment arms, is as follows: On the right side of the machine a bar 103 is pivoted to the arm 92, (see Fig. 10) its other end having a slot 104 riding on a fixed pin 105. The bar 103 carries a lug 106 that is engaged by an arm 107 carried by the bar 53, at the extreme forward movement of the bar, and thereby the arm 92 will be swung to move the restoring bar 90 forward. An elbow lever has one arm 98 provided with a catch 981 arranged to engage a lug 96 on the arm 92, to thereby lock the arm 92 and prevent its being returned by a spring 88. But the latch is so positioned that the bar 92 can be given a slight rearward movement on the return of the bar 103 before these parts 96 and 981 engage to lock the restoring bar in such position. This is for the purpose of swinging the depending arms 81 sufficiently forward to permit the detent arm to rise and engage the catch with the ear 82, and thereupon the restoring bar that will be held by the latch 98, will be offset a slight distance from the depending arm 81. This will also permit the slight rearward movement of the depending arm 81 when the detent is tripped. The further rearward movement of the bar 53 will not interfere with the position of the arm 92 and the restoring bar until a depending arm 982 of the elbow lever, that is held in latched position by a spring 100, is engaged by a pin 983 on the bar 53 to cause this elbow lever to be tripped, releasing the arm 92 and the restoring bar. But this engagement 125 of the pin 983 with the arm 982, by the position of the pin, is not effected until the final part of the rearward movement of the bar 53, after the universal bar has been returned to its normal lowermost position and 130

the toggle broken, as has been described. The arm 91 engages a stop pin 910 when drawn back by its spring 911. (See Fig. 5.) On the opposite side of the machine a similar construction is provided, (see Fig. 7) the arm 97 being drawn rearwardly by a spring 99 to engage a stop pin 101. A bar 200 is pivoted to the arm 91 and guided at its slotted portion 202 on a pin 203. This bar 200 carries a lug 204 that is engaged by an arm 205 fast on a bar 120 corresponding to the bar 53 on the opposite side of the machine. The shaft 60 operated by the handle 61, extends across the machine and 15 on the left side carries a crank arm 126 pivoted to the bar 120 by which the bar will be swung from the handle. At its rear the bar 120 has a slot 206 in which rides a crank pin 207 fast on a crank 125 secured to the 20 shaft 49, that extends through the machine and which connects with the main operating springs 170, as before described. This bar is also provided with a toggle formed of a link 121 and an elbow 122 coöperating 25 with a pin 123 identical with the construction on the opposite side of the machine, and hence need not be further described. The bars 120 and 53 will therefore swing back and forth in unison from the operation 30 of the handle and the main spring. By the said means the arms 92 and 93 will be similarly controlled by the bars 120 and 53. An elbow lever 97 engages a lug 95 on the arm 91 similar to the opposite side of 35 the machine, and a pin 101 on the bar 120 trips this latch in the same manner, the latch being controlled by a spring 99.

The side lever 77, by means of which the numeral pinions are shifted to engage alternately with the rack bars and with the toothed segments, extends downwardly on the left side of the machine, (see Fig. 5,) and is pivoted to a bar 144. The forward end of this bar carries a pin 145 riding in a 40 suitable slot in the side frame to guide this bar. The bar 120 is provided with a slot through which the pin 145 extends, and as the bar 120 moves back and forth the end walls 146 and 147 of this slot alternately 45 engage the pin 145 at the extreme forward and rearward parts of the movement of this side bar. By this means, the arm 77 will be alternately swung back and forth a sufficient distance to carry the pinions to engaging position. Suitable means are provided for holding the lever 77 in these two 50 positions, shown in the form of an arm 140, pivoted in the frame, and carrying a stop pin 141 having its upper edge in the form 55 of a ridge. This arm is pressed upwardly by a spring 142 to engage alternately with notches 143 in the lower edge or end of the lever 77. These notches will be engaged by the pin at the two said extreme positions of

the lever and retain the pinions in said positions until shifted by the reverse movement of the bar 120. 65

In the construction of this machine suitable mechanism is provided whereby when none of the keys and stop bars of a row, or 70 rows, have been depressed, the rack-bar corresponding therewith is locked in its normal lowermost position and prevented from rising with the universal bar. In front of each of the rack bars is a lock plate 151, shown in 75 Fig. 14, that is provided with a spring 210 pulling it forwardly and upwardly. This plate has a bent portion 156 arranged to be engaged by the extremity of the stop bars 9 so that when any stop bar is advanced it 80 will cause the plate 151 to swing rearwardly. The bent portion 156 engages a projection 63 on each rack bar in the normal position of the plate 151, but when this plate is moved backwardly by the stop bar, as described, the 85 rack bar will be free to rise upon the swinging of the universal bar. Therefore, in each row where no key is depressed, this plate will arrest the rack bar and prevent its elevation when the universal bar rises. The 90 plate 151 also carries a stop in the form of a roller 157, see Fig. 14, positioned just above the lever 19 as shown in Fig. 1, whereby upon depressing the plate 151, that is normally suspended by a spring 210 connected 95 with a stationary part of the machine, this lever 19 will be swung to elevate its top latch plate 16, thereby restoring any keys of that particular bank that may have been advanced by the depression of the projecting 100 end 152 of the plate. This constitutes what is termed the "column release".

Means are further provided for swinging the whole set of stop plates 151 rearward to shift the bent portion 156 out of engagement 105 with the stops 63 on the rack and type plates. A shaft 158 is mounted in the two side plates and carries a shutter 159 that, when the shaft is swung, will strike the lower portion of the lock plate and swing it 110 rearward. This shaft 158 at the left side of the machine, carries a crank 160, see Fig. 6, on which is a pin 161. The crank is normally pulled upward by a spring 162 so that pin 161 will lie above a cam plate 163, carried by the side bar 120. On this side bar is mounted a lever 127 swinging on a pivot 128, the lever being normally pulled upward at its rear end by a spring 137. (See Figs. 7 and 8.) But when the lever 127 is pulled 115 upward at its front end by means described hereinafter, it will engage the pin 161 and place the pin in position to engage the front curved end of the cam 163, and upon forward movement of the side bar 120 from 120 swinging of the handle, the crank 160 will be swung downward to rock the shutter, and shift the shutter rearward, causing the stop 125

plates to release all of the rack and type bars. This is done when it is desired to take a total, or a sub-total, on the machine.

At one side of the machine is a total key 132 vertically movable and carrying a pin 135 engaging a spring 134 to normally move the key upward. At the lower end of the key-stem 132 is a hook portion 133 that when the key is depressed, will engage a similar hook 130 carried by the swinging lever 127, as indicated in Figs. 8 and 9, the stem and lever having a certain lateral movement from resilient construction. When the key is depressed these hooks will engage and upon release the key will move upwardly and swing the lever 127. This will hold the lever swung for a certain period, to operate the shutter 159 as just described, releasing all of the rack and type plates from the said stop plates 151. On the side bar 120 is a stop or ledge 131 that projects over the lever 127 and is engaged by the top edge of the same when the stem 132 is depressed to hook on to the lever hook 129 and elevate the lever, as indicated in Fig. 9. Upon this position of these parts, and the handle being swung forward, the side bar 120 will move forward carrying with it this lever 127 that is pivoted thereon. This forward movement will carry the lug 129 forward beyond the hook 133 of the key-stem, thus releasing lever 127, the hook being retained lowered by the lug 131 on the side bar. But during this operation the side bar has carried the cam 163 forward during the depressing of the crank 160 by the pin 161 engaged by the lever, so that the pin 161 will be held down during the balance of the forward movement of the side bar by this cam plate 163. As the side bar continues forward a lug 130 on the lever 127 higher than lug 129, moves over the hook portion 133 so that upon further movement of the side bar the hook 133 disengages the lug 131 and engages merely the lug 130. When the hook 133 of the stem released the lug 129 of the lever, its forward end was again depressed by its spring 137, but which did not bring the lug 130 below the plane of the lug 131, on the key stem. Therefore the engagement of this lug 130 with the hook 133 of the key stem will permit the latter by its spring to be elevated and swing the front end of the lever 127 to depress a second time the rear end of the lever 127, as indicated in Fig. 7. This represents the limit of the forward movement of the side bar with its lever, and as the side bar starts its return movement to the rear, the lug 130 will very soon pass beyond the hook 133 of the key stem, and is now above the lug 131 on the side bar, leaving the key stem free to rise to its normal position, and the lever 127 free to be returned by its spring, so far as this key stem is concerned.

A sub-total key is provided having a stem 65 175 that is vertically slidable in suitable guides, the lower end of the stem having a hook 176 that when the key is depressed will hook under the said lug 130 of the lever 127. It is to be understood that the lever 127 has 70 a slight lateral spring movement, or the key stem, or both, by reason of their resilient construction. On depressing this key and thus engaging its hook, it will be held depressed after the lever 127 is swung upward a short distance. But as soon as the side bar 120 starts to move forward, the lug 130 is carried beyond the hook 176 of the key stem, thereby releasing the key stem to rise to normal position, and also 75 80 permitting the lever 127 to return to normal position.

On the left side of the machine above the side bar 120, see Figs. 5-9, is a bar 230 arranged adjacent the key stems 132 and 175, 85 and at its rear end is supported by a crank 231 suitably pivoted whereby this bar can swing up and down. A spring 232 connected to the bar 230 moves it upward to engage the lug 135 on the total key stem 132. 90 When this key is depressed the key will rock this end of the bar downward; and this also occurs when the sub-total key 175 is depressed, a pin 375 thereon engaging the bar to swing it downward. A link 116 is 95 pivoted at 117 on the bar 230, its lower end containing a slot 119 into which projects the pin 118 carried by a lever 112 fast on a rock shaft 111 extending across the machine. This lever has a slot 223 into which 100 projects a pin 240 carried by a link 220 whose lower forked end slides on a guide-pin 222. The upper end of link 220 engages the head of a bar 200 that is pivoted to the arm 91 that swings the restoring bar 90. 105 Bar 200 has a slot 202 that is somewhat L-shaped and through which projects a pin 203 that is stationary on the side plate. Bar 200 carries a lug 204 arranged to engage a stop 205 fast on the side bar 120. In the 110 normal position of the bar 230, when neither the sub-total or total keys are depressed, the link 116 will be in its upper position with the rear end of lever 223 depressed, and the link 220 will be lowered permitting 115 a spring 224 to pull the bar 200 downward whereby its stop 204 will lie below the beak of the stop 205 on the side bar 120, as indicated in Fig. 5. This is the normal position of the parts for setting up items on the machine, and when the handle is swung and the side bar 120 moved forward, the rear portion of the stop 205 will engage the lug 204 whereby at the final portion of the forward stroke the arm 91 will be swung forward a short distance; and as the side bar begins to return the bar 120 will be quickly released to be moved back to its former posi- 120 125

tion by its spring 911. On the opposite side of the machine a lever 110 is fast on the shaft 111 just described, and in the upper normal position of the bar 120 the lever 5 will be lowered, as indicated in Fig. 10, and a link 108 carrying a pin 102' sliding in a slot 113 in the lever 110, will be lowered to permit a spring 114 to pull the bar 103 downward, whereby lug 106 on the bar 103 10 can be engaged by the stop 107 when the side bar 53 is moved forward. This will swing the arm 92 forward to advance the restoring bar 90. It will be understood that by this means the arms 91 and 92 are simultaneously swung forward, to be engaged by the latches 97 and 98, respectively. These two bars will remain in the forward position engaged by these latches until in the return movement of the side bars the pins 15 983 and 101 shift the latches to release the arms, that will be returned by their springs to bring the restoring bar back to normal position. But when the side bar 230 is depressed by pushing down either the total 20 or sub-total key, through the link 116 and lever 112, the shaft 111 will be rocked, and the two side bars 200 and 103 will be elevated by the respective links 108 and 220, so that the lug 106 will be positioned above 25 the stop 107 and the lug 204 will now lie above the stop 205. Hence the reciprocation of the side bars will not cause engagement of these lugs 106 and 204 with the stops on the side bars, and the arms will not 30 swing the restoring bar 90.

The lever 127 that is pivoted on the side bar 120 carries a lug 136 that when the lower end of this lever is swung on the side bar can engage the pin 138 on the inner 40 face of the side lever 77, which latter serves to shift the numeral pinions into and out of engagement with the racks 73. In the normal reciprocation of the side bar 120, the stop 136 is held free from engagement with 45 the pin 138. But when the total key 132 is depressed, this stop 136 is lowered, and as soon as the side bar starts forward, the forward edge of the lug 136 now engaging the pin 145, (see Fig. 8,) will swing the 50 lever 77, so that the numeral wheels are at once thrown into engagement with the racks. As soon as the hook 129 leaves the hook 133 of the key stem 132, the lever will swing and the lug 136 will rise disengaging the 55 pin 138, but the arm 77 will be locked in this position by the arm 140, as described.

As the side bar moves forward carrying the lever 127, the hook 129 will shortly disengage the hook 133 permitting the lever 60 127 to swing up at its rear, thereby freeing the pin 138 from the stop 136. On continued movement of the side bar, after the hook 133 has passed lug 131 and engages the lug 130, the lever 127 will be again swung to 65 the position indicated in Fig. 7, in which

pin 138 lies at the rear of the stop 136, and this is the forward position of the side bars. As soon as the side bar starts to move rearward, the stop 136 engaging this lug will swing lever 77 to move the pinions away 70 from the rack bars, and thereupon the key stem 132 being freed from the lug 130 the lever 127 will swing to free the pin 138 from the stop 136; but as stated the lever 77 has now been swung to free the pinions from 75 the rack bars, which is the normal position of these parts. But when the sub-total key is depressed and the lever 127 is swung, the pin 138 will be similarly engaged, by the stop 136 at the initial movement of the 80 side bar to swing the pinions into engagement with the rack bars. But as described the forward movement of the side bar will quickly disengage the hook 176 of the sub-total key 175, whereby the lever will be 85 returned to normal position, disengaging the pin 138 from the stop 136. The lever 77 will remain in this position until the final portion of the return stroke when the abutment 147 will strike the pin 138 and return the lever 77 to normal forward position with the pinions free from the rack bars.

The operation of the device in connection with the total and sub-total keys, is as follows: It is presumed that a number of items have been set up in the machine by the operation of the numeral keys 7, and the numeral wheels 74 have been set by the operation of the rack and type bars and other 90 parts, as has been described. When it is desired to take a total, it is not necessary to give an extra swing to the main operating handle 61 as is required in some of the machines of this class. It is only necessary to 95 depress the total key 132, that will lock in its depressed position, and therefore the key 132 does not have to be held down until the final operation of the handle or operating shaft as is necessary in certain machines of 100 this class. As soon as the handle is swung, the crank 160 will be shifted and the cam 163 will swing the shutters to release stop plates 151; which operation is effected while the toggle links are being straightened out and hence before any movement is given to the universal bar 46. At the same time the lever 77 will be swung to throw the numeral wheels into engagement with the rack bars, and the further movement of the handle will elevate the universal bar permitting all of the type bars to move upward in contact with the numeral wheels. It will be understood that when the adding operation is taking place, the racks only engage the 105 numeral wheels on their downward movement, but now the racks engage the numeral wheels on the upward movement of the racks and hence they will move the numeral pinions in the reversed direction, that 110 115 120 125 130

will be arrested when the stop or cam 87 strikes the stop 86 of each of the detents. From this it will be understood that if a numeral wheel has been set to 5 in the adding operation, it will now rotate from 5 back to 0, which is five points and stop at this position. This will bring the number 5 opposite the printing position on the type carrier, and the same applies to all of the 10 other racks and numeral pinions. The printing operation, by the means set forth in Fig. 22, is timed to be effected at the latter part of the forward movement of the side levers. But as soon as the side bar begins its 15 rearward movement the lever 77 is swung by the described means to move the numeral pinions forward free from the rack 73. At this stage the universal bar will be in its uppermost position, and since no key 20 stops are advanced, the racks will be freed from the pinions and will all rise to engage the universal bar, except those in the 25 9 position, and the return of the universal bar will move the racks downward to their normally lowermost position. As stated, the rack bars will rotate each of the pinions back to its 0 position, and therefore the machine will be restored to position for starting a new operation, the total having been 30 printed by the printing mechanism.

In the operation of the sub-total, on depressing the sub-total key at the side, it will be engaged and held down, and it is not necessary to retain pressure on the key. As 35 described, the shutter will be swung to release all of the rack and type plates, and the pinions will be swung rearward to engage the rack bars previous to any movement upward of the universal bar. As the 40 universal bar moves upward, the engagement of the rack 73 with the numeral pinions will swing these all backward to the 0, thereby setting up the total that was in the machine to be printed by the printing mechanism, at the final forward movement of the 45 side bars and handle. But the rack bars are held in engagement with the numeral pinions, so that on the downward movement of the rack and type plates, caused by the 50 universal bar, the numeral wheels will be rotated in the reverse direction that they were turned when the racks were permitted to rise, and for precisely the same differences, therefore the total that was in the 55 machine, as indicated by these numeral wheels, will be restored and hence kept in the machine, at the initial part of this rearward movement, the pinions will be again swung forward to their normal position but 60 the positions of the pinions at the beginning of the operation is now the same.

The carrying mechanism set forth is not claimed herein, but forms subject matter of another application, Serial No. 737,818.

65 A key-stem 148, held up by spring 150,

has a slotted lower end 149 riding on pin 145 on arm 144. When the key is depressed and held down it rocks bar 144 holding pin 145 out of engagement with the abutments 146 and 147, whereby when side bar 120 is 70 moved forward and back the lever 77 will not be swung, and the pinion will not engage the racks, and no adding will be performed.

Having thus described my invention, I 75 claim:

1. The combination with a set of rack bars and adding devices operatively connected therewith, of a series of sets of stop bars, means for advancing the rack bars 80 when released from normal position, and a set of movable stop plates, one for each rack bar arranged adjacent thereto, connecting means between each plate and its rack bar for retaining the rack bar in normal position, each plate having a portion arranged to coöperate with one set of stop bars whereby when any stop bar of the set is advanced the plate will be shifted to release the appropriate rack bar, said stop plate being 85 also supported for longitudinal movement, each set of stop bars having coöoperating therewith a release member projecting into the path of the stop plate, and a stop on the stop plate arranged to engage said latter 90 member for movement when the plate is depressed to release the stop bars connected therewith.

2. The combination with a set of rack bars and adding devices operatively connected therewith, of a series of sets of stop bars, means for advancing the rack bars 100 when released from normal position, and a set of movable stop plates, one for each rack bar, arranged adjacent thereto, connecting 105 means between each plate and its rack bar for retaining the rack bar in normal position, each plate having a portion arranged to coöperate with one set of stop bars whereby when any stop bar of the set is advanced, the plate will be shifted to release the appropriate rack bar, and a release plate arranged in proximity to all of the stop plates for engagement therewith when moved to cause all of the stop plates to be shifted to 110 release the rack plates.

3. The combination with a set of rack bars and adding devices operatively connected therewith, of a series of sets of stop bars, means for advancing the rack bars 115 when released from normal position, a set of movable stop plates, one for each rack bar arranged adjacent thereto, connecting 120 means between each plate and its rack bar for retaining the rack bar in normal position, each plate having a portion arranged to coöperate with one set of stop bars whereby when any bar of the set is advanced the plate will be shifted to release the appropriate 125 rack bar, each plate being provided with 130

a suitable guide way at its top and bottom ends for endwise movement and to permit the lower end to swing, and a spring connected with each plate and arranged to draw the plate upwardly and to also draw its rear end forwardly.

4. In an adding machine, the combination with an actuating shaft, a side bar reciprocated by said shaft, a set of rack bars, a universal bar operatively connected with the side bar to be swung to return the rack bars and hold them in normal position, a carrier, a set of numeral pinions on the carrier shifted thereby to engage and disengage the rack bars, an arm on the carrier provided with a stop pin, an abutment on the side bar arranged to engage said pin as the side bar is advanced from the operating shaft at the latter part of its movement to shift the pinions to engage the rack bars after the universal bar has been raised, a second abutment on the side bar arranged to engage said pin on the return of the side bar after the universal bar has returned the rack bar to normal position, to disengage the pinions.

5. In an adding machine, the combination with an actuating shaft, a side bar reciprocated by said shaft, a set of rack bars, a universal bar operatively connected with the side bar to be swung to return the rack bars and hold them in normal position, a carrier, a set of numeral pinions on the carrier shifted thereby to engage and disengage the rack bars, an arm on the carrier provided with a stop pin, an abutment on the side bar arranged to engage said pin as the side bar is advanced from the operating shaft at the latter part of its movement to shift the pinions to engage the rack bars after the universal bar has been raised, a second abutment on the side bar arranged to engage said pin on the return of the side bar after the universal bar has returned the rack with the bar to normal position to disengage the pinions, a connection between the side bar and the universal bar whereby the universal bar is caused to elevate after the initial movement of the side bar, and on return of the side bar the universal bar is brought to rest before the final return movement of the side bar, whereby the universal bar will return the rack bars to normal position before the pinions are shifted to disengage therefrom.

6. In an adding machine, the combination with an actuating shaft, a side bar reciprocated by said shaft, a set of rack bars, a universal bar operatively connected with the side bar to be swung to return the rack bars and hold them in normal position, a carrier, a set of numeral pinions on the carrier shifted thereby to engage and disengage the rack bars, an arm on the carrier provided with a stop pin, an abutment on the side bar arranged to engage said pin as the side bar is advanced from the operating shaft at the

latter part of its movement to shift the pinions to engage the rack bars after the universal bar has been raised, a second abutment on the side bar arranged to engage said pin on the return of the side bar after the universal bar has returned the rack with the bar to normal position to disengage the pinions, a connection between the side bar and the universal bar whereby the universal bar is caused to elevate after the initial movement of the side bar, and on return of the side bar the universal bar is brought to rest before the final return movement of the side bar, whereby the universal bar will return the rack bars to normal position before the pinions are shifted to disengage therefrom, a total operating device on the machine arranged upon operation of the actuating shaft to cause the side bar to engage said pin to shift the pinions to engage the rack bars before the universal bar rises and retain the pinions engaging the rack bars during the forward movement of the side bar, said means being operative to shift the pinions to disengage the rack bars at the end of the forward movement of the side bar.

7. In an adding machine, the combination with an actuating shaft, a side bar oscillated by said shaft, a set of rack bars, a universal bar operatively connected with the side bar to be reciprocated to return the rack bars and hold them in normal position, a carrier, a set of numeral pinions on the carrier shifted thereby to engage and disengage the rack bars, an arm on the carrier provided with a stop pin, an abutment on the side bar arranged to engage said pin as the side bar is advanced from the operating shaft at the latter part of its movement to shift the pinions to engage the rack bars after the universal bar has been raised, a second abutment on the side bar arranged to engage said pin on the return of the side bar after the universal bar has returned the rack with the bar to normal position, a connection between the side bar and the universal bar whereby the universal bar is caused to elevate after the initial movement of the side bar, and on return of the side bar the universal bar is brought to rest before the final return movement of the side bar, whereby the universal bar will return the rack bars to normal position before the pinions are shifted to disengage therefrom, a total operating device on the machine arranged when depressed upon operation of the actuating shaft to cause the side bar to engage said pin to shift the pinions to engage the rack bars before the universal bar rises and retain the pinions engaging the rack bars during the forward movement of the side bar, said means being operative to shift the pinions to disengage the rack bars at the end of the forward movement of the side bar, and a sub-total key member connected with said

total operating device and constructed and arranged to cause the carrier to swing the pinions to engage the rack bars at the initial movement of the side bar, and to retain the pinions engaged with the rack bars until the latter portion of the return stroke of the side bar.

8. The combination of adding devices and a universal bar, of an actuating member, a spring operated shaft directly connected with the universal bar, a side bar operated by the actuating member, a spring connection between the spring shaft and the side bar operable to cause additional movement of the side bar after the spring shaft has returned the universal bar to normal position, a set of key members, and locking means for the key members connected with the side bar whereby the key members are locked on the initial movement of the side bar before the universal bar begins to move from normal position.

9. The combination of adding devices and a universal bar, of an actuating member, a spring operated shaft directly connected with the universal bar, a side bar operated by the actuating member, a spring connection between the spring shaft and the side bar operable to cause additional movement of the side bar after the spring shaft has returned the universal bar to normal position, a set of key members, and locking means for the key members connected with the side bar whereby the key members are locked on the initial movement of the side bar before the universal bar begins to move from normal position, and all retained locked until the return of the universal bar to normal position during the final return movement of the side bar.

10. The combination of a set of key stems, a stop-bar operatively connected with each key-stem to be advanced thereby, a spring for retracting each bar when advanced by its stem, a latch bar supported for movement transverse to the stop-bars, a set of latch pins on the latch bar one for each stop-bar, a spring on the latch bar arranged to normally retain the bar with the pins each adjacent one of the stop bars, and a lug on each stop bar arranged to engage one of the pins on the latch bar to shift the latch bar when the stop bar is advanced, the lugs each serving to engage the pin and shift the latch bar when the stop bar is advanced by the key stem, the lugs also serving to engage the corresponding pins as the stop bars are returned by their springs whereby the latch bar holds the stop bars in advance position until the latch bars are shifted to release the stop bars, and a slotted plate through which the stop bars pass and against which the said lugs are normally held by said springs.

65 11. The combination with the restoring

bar, and controlling means, and the side bars, of a swinging side member, a total key and a sub-total key arranged to shift the side member, a rock shaft extending across the machine, a lever on each side of the machine fast on the shaft, a link connecting one said lever with the said side member to rock said shaft when either of said keys is depressed, arms one on each side of the machine connected to the restoring bar, a bar on each side pivoted to the arms respectively, a lug on each said bar, a stop on each side bar arranged to engage said lugs to swing the restoring bar, said levers each having a link thereon arranged to engage the said bars respectively to elevate the bars when the shaft is rocked by said means, whereby the stops on the side bars will not engage the lugs on said bars.

12. In a calculator, the combination with the rack bars and the adding pinions movable to and from the rack bars, of a side lever connected with the pinions to shift them to and from the rack bars, a side bar on the machine arranged to move back and forth, a pin on the side bar, a lever pivoted on the side bar and provided with a lug arranged to coöperate with said pin, means for normally retaining the lever on the side bar with its lug out of position for engagement with said pin, a total key on the machine having a stem movable adjacent the side bar and its lever, a hook on said stem, the side bar and its lever having lugs co-operating with said hook when the stem is advanced whereby to shift the side bar lever into engagement with said side lever pin to cause the pinions to be shifted to engage the rack bars at the initial part of the advance movement of the side bar and to release the side bar lever when swung free from said pin upon further advance of the side bar, said lugs and hook upon initial part of the return movement of the side bar and lever again swinging the side bar lever to cause its lug to engage the side lever pin to thereby cause the side lever to retract the pinions from the rack bars, and upon further advance movement of the side bar and its lever the latter is released to be free from the side lever pin.

13. In a calculator, the combination with the rack bars and the adding pinions movable to and from the rack bars, of a side lever connected with the pinions to shift them to and from the rack bars, a side bar on the machine arranged to move back and forth, a pin on the side bar, a lever pivoted on the side bar and provided with a lug arranged to coöperate with said pin, means for normally retaining the lever on the side bar with its lug out of position for engagement with said pin, a total key on the machine having a stem movable adjacent the side bar and its lever, a hook on said stem, the side bar and its lever having lugs co-operating with said hook when the stem is advanced whereby to shift the side bar lever into engagement with said side lever pin to cause the side lever to retract the pinions from the rack bars, and upon further advance movement of the side bar and its lever the latter is released to be free from the side lever pin.

- bar and its lever having lugs coöperating with said hook, means for drawing the stem upwardly when depressed, the side bar and stem having relative lateral movement permitting the lug to pass said hook on the depression of the stem whereby the lugs and stem upon initial part of advance movement of the side bar will shift the side bar lever into engagement with said side lever pin to shift the pinions to engage the rack bars, and to release the side bar lever to be swung free from said pin upon further advance of the side bar, said lugs and hook upon initial part of the return movement of the side bar and lever again swinging the side bar lever to cause its lug to engage the side lever pin to thereby cause the side lever to retract the pinions from the rack bars, and upon further advance of the side bar and its lever the latter is released to be free from the side lever pin.
14. In a calculator, the combination with the rack bars and the adding pinions movable to and from the rack bars, of a side lever connected with the pinions to shift them to and from the rack bars, a side bar on the machine arranged to move back and forth, a pin on the side bar, a lever pivoted on the side bar and provided with a lug arranged to coöperate with said pin to swing the side lever, means for normally retaining the lever on the side bar with its lug out of position for engagement with said pin, a total key on the machine having a stem movable adjacent the side bar and its lever, a spring for retracting the key when depressed, a hook on said stem, a lug on said lever arranged to be engaged by said key hook when depressed to swing the lever for engagement with said pin and retaining the stem depressed, a lug on the side bar arranged to engage said stem hook upon advancement of the side bar before the hook leaves the lever lug to retain the stem depressed permitting the lever to return to normal position upon further advancement of the side bar, a second lug upon said side bar lever arranged to engage the stem hook upon further advance of the side bar and lever and, upon release of the hook by the said side bar lug the second lever lug will be engaged by said hook solely to again swing the lever to position of engagement with said side lever pin, said second lever lug upon retraction of the side bar releasing the hook stem at the initial movement of the bar.
15. In a calculator, the combination with the rack bars and the adding pinions movable to and from the rack bars, of a side lever connected with the pinions to shift them to and from the rack bars, a side bar on the machine arranged to move back and forth, a pin on the side bar, a lever pivoted on the side bar and provided with a lug arranged to coöperate with said pin, means for normally retaining the lever on the side bar with its lug out of position for engagement with said pin, a total key on the machine having a stem movable adjacent the side bar and its lever, a spring for retracting the key when depressed, a hook on said stem, a lug on said lever arranged to be engaged by said key hook when depressed to swing the lever for engagement with said pin and retaining the stem depressed, a lug on the side bar arranged to engage said stem hook upon advancement of the side bar before the hook leaves the lever lug to retain the stem depressed permitting the lever to return to normal position upon further advancement of the side bar, a second lug upon said side bar lever arranged to engage the stem hook upon further advance of the side bar and lever and, upon release of the hook by the said side bar lug the second lever lug will be engaged by said hook solely to again swing the lever to position of engagement with said side lever pin, said second lever lug upon retraction of the side bar releasing the hook stem at the initial movement of the bar.
16. In a calculator, the combination with the rack bars and the adding pinion movable to and from the rack bars, of a side lever connected with the pinions to shift them to and from the rack bars, a side bar on the machine arranged to move back and forth, a pin on the side bar, a lever pivoted on the side bar and provided with a lug arranged to coöperate with said pin to swing the side lever, means for normally retaining the lever on the side bar with its lug out of position for engagement with said pin, a total key on the machine having a stem movable adjacent the side bar and its lever, a spring for retracting the key when depressed, a hook on said stem, a lug on said lever arranged to be engaged by said key hook when depressed to swing the lever for engagement with said pin retaining the stem depressed, a lug on the side bar arranged to engage said stem hook upon advancement of the side bar before the hook leaves the lever lug to retain the stem depressed permitting the lever to return to normal position upon further advancement of the side bar, a second lug upon said side bar lever arranged to engage the stem hook upon further advance of the side bar and lever and, upon release of the hook by the said side bar lug the second lever lug will be engaged by said hook solely to again swing the lever to position of engagement with said side lever pin, said second lever lug upon retraction of the side bar releasing the hook stem at the initial movement of the bar.

of the side bar and lever, and upon release 5 of the hook by the said side bar lug the second lever lug will be engaged by said hook solely to again swing the lever to position of engagement with said side lever pin, said second lever lug upon retraction of the side bar releasing the hook stem at the initial movement of the bar, a sub-total key on the machine having its stem movable adjacent the side bar and its lever and provided with a hook arranged to coöperate with said side bar lever causing the lever to engage said second lever lug to swing the side bar lever at the initial portion of the 10 advance movement causing the pinions and rack bars to engage, said hook and lug disengaging upon further movement of the side bar to release both such members, and means for causing the side bar at the latter 15 part of its return movement to swing the side lever and retract the pinions from the rack bars.

17. In a calculator, the combination with the rack bars and the adding pinions and 20 the carrying devices, of a restoring bar for controlling the carrying devices, an arm pivoted on each side of the machine to which the carrying bar is secured at its ends, stops for said arms, springs to draw the arms 25 against the stops, a lug on each arm, a bent lever pivoted on each side of the machine and having a hook end arranged to engage the lugs respectively to hold the restoring bar in an intermediate position with the 30 arms free from the stops, a side bar on each side of the machine, a pin on each side bar arranged to engage one of the bent levers to shift said hook portions and release the arms and bars, a bar pivoted on each side of the 35 machine to one of said arms and guided to move back and forth and each provided with a lug, and a stop on each of the side bars arranged to engage said lugs respectively to advance the bars and arms and restoring 40 bar to a third position and permit reengagement of the hook levers when said lugs are released from the stops.

18. In a calculator, the combination with the rack bars and the adding pinions and 45 carrying devices, of a restoring bar for controlling the carrying devices, an arm pivoted on each side of the machine to which the carrying bar is secured at its ends, stops for said arms, springs to draw the arms 50 against the stops, a lug on each arm, a bent lever pivoted on each side of the machine and having a hook end arranged to engage the lugs respectively to hold the restoring bar in an intermediate position with the 55 arms free from the stops, a side bar on each side of the machine, a pin on each side bar arranged to engage one of the bent levers to shift said hook portions and release the arms and bars, a bar on each side of the machine 60

pivoted to one of said arms, means for 65 guiding the said latter bars to move back and forth and also to swing at its end remote from said arm, a lug on each latter bar, a stop on each of the side bars arranged to engage said latter lugs respectively to advance the bars and arms and restoring bar to a third position for reengagement of the hook levers when the stops release said lugs, a totaling device on the machine, and means 70 connected with the totaling device arranged to shift said bars to bring their lugs out of position for engagement with the stops on the side bars.

19. In a calculator, the combination with the adding and the carrying devices, of a restoring bar for controlling the carrying devices, an arm pivoted on each side of the machine to which the carrying bar is secured at its ends, stops for the arms, springs to draw the arms against the stops, a lug on 80 each arm, a bent lever pivoted on each side of the machine having a hook end arranged to engage the lugs respectively, a side bar on each side of the machine, a pin on each side bar arranged to engage one of the bent levers to shift said hook portions and release the arms and bars, a bar on each side of the machine pivoted to one of said arms by one end with its other end slotted, pins 85 engaging the latter slotted portions to guide the bars, the latter bars each having a lug, a stop on each of the side bars arranged to engage the latter lugs respectively to advance the bars and swing the arms and restoring bar, a shaft extending across the machine, an arm on each end of said shaft, a slide pivoted to one end of each latter arm and arranged to engage said slotted bars to shift them when the shaft is swung and bring the lugs on said bars out of position 90 for engagement with the stops on the side bars, a totaling device on the machine, and means connected with the latter device arranged to swing said shaft to prevent shifting of the restoring bar upon movement of 95 the side bars.

20. In a calculator, the combination with the adding and the carrying devices, of an arm pivoted on each side of the machine, a restoring bar secured to said arms and arranged to control the carrying devices, stops for said arms, springs to draw the arms against the stops, a lug on each arm, a bent lever pivoted on each side of the machine having a hook end arranged to engage the 100 lugs respectively, a side bar on each side of the machine, a pin on each side bar arranged to engage one of the bent levers to shift said hook portions and release the arms and bar, a bar on each side of the machine pivoted to 105 one of said arms by one end, means for guiding the other end of said bars to move back and forth and also to swing, a lug on 110

each said latter bar, a stop on each of the side bars arranged to engage the latter lug respectively to advance the arms and restoring bar, a totaling device on the machine, a 5 sub-totaling device on the machine, and means connected with both latter devices arranged to shift said bars; when each of the devices are operated, to bring their lugs out of position for engagement with the stops 10 on the side bars.

21. In a calculator, the combination with a set of rack bars and adding devices connected therewith, a series of sets of stop bars for the rack bars, and means for advancing 15 the rack bars when released from normal position, of a set of movable stop plates one for each rack bar, means for causing each plate to retain its rack bar in normal position, a shaft extending across the machine, a 20 shutter fast on said shaft and arranged to engage all said stop plates when swung from normal position to shift the plates to release all of the rack bars, a crank arm on said shaft at one side of the machine, a pin 25 on the crank arm, a side bar on the machine that is moved back and forth in the operation of the machine, a cam on the side bar, a total device on the machine having means 30 arranged to swing said crank to bring its pin into position for engagement with the cam on the side bar and thereby cause the shutter to be swung to release all of the rack bars at the initial movement of the side bar.

22. In a calculator, the combination with 35 a set of rack bars and adding devices connected therewith, a series of sets of stop bars for the rack bars, and means for advancing the rack bars when released from normal position, of a set of movable stop plates one for each rack bar, means for causing each plate to retain its rack bar in normal position, a shaft extending across the machine, a shutter fast on said shaft and arranged to engage all said stop plates when 40 45 50 55 60 65 70 75 80 85 90 95 100 105 110 115 120 125 130 135 140 145 150 155 160 165 170 175 180 185 190 195 200 205 210 215 on the machine that is moved back and forth in the operation of the machine, a cam on the side bar, a spring connected with the crank arm, a lever pivoted on the side bar, a total key on the machine, a sub-total key on the machine, each of said keys when depressed being arranged to swing said lever to engage the crank and shift its pin to position for engagement with the 5 cam on the side bar whereby the shutter will be swung to release all of the rack bars at the initial movement of the side bar, said cam being arranged to retain the shutter so shifted until the return of the side bar 10 to normal position.

26. In a calculator, the combination with a set of rack bars, a set of numeral pinions movable to engage and disengage the rack bars to be advanced thereby, a series of 20 sets of stop bars for the rack bars, means for advancing the rack bars, a side bar on the machine arranged to move back and forth in the operation of the machine, means connected with the side bar for shifting 25 the numeral pinions to engage the rack bars at the latter portion of the advance movement of the side bar, a lever pivoted on the side bar, a total key on the machine arranged to engage said lever, means connected with said lever whereby the depression of the lever by said key will cause the numeral pinions to be shifted to engage the rack bars at the initial part of the advance of the side bar, a set of movable stop 30 plates one for each rack bar, means for causing each plate to retain the rack bar in normal position, a shaft extending across the machine, a shutter on said shaft arranged to engage all said stop plates when 35 40 45 50

swung from normal position to shift them to release all of the rack bars, a crank arm on said shaft at one side of the machine, a pin on the crank arm arranged to engage said lever, and a cam on the side bar arranged to engage said crank pin when the latter is shifted from normal position by said lever to thereby swing said shutter at the initial advance of the side bar to release all of the rack bars at such stage in the operation.

27. In a calculator, the combination of a set of rack bars, a set of numeral pinions movable to engage and disengage the rack bars to be advanced thereby, a series of sets 55 of stop bars for the rack bars, means for advancing the rack bars, a slide bar on the machine arranged to move back and forth in the operation of the machine, means connected with the side bar for shifting the numeral pinions to engage the rack bars at the latter portion of the advance movement 60 of the side bar, a lever pivoted on the side bar, a total key on the machine arranged to engage said lever, a sub-total key on the machine also arranged to engage said lever,

means connected with said lever whereby the depression of the lever by either of said keys will cause the numeral pinions to be shifted to engage the rack bars at the initial part of the advance of the side bar, a set of 70 movable stop plates one for each rack bar, means for causing each plate to retain the rack bar in normal position, a shaft extending across the machine, a shutter on said shaft arranged to engage all said stop plates 75 when swung from normal position to shift them to release all of the rack bars, a crank arm on said shaft at one side of the machine, a pin on the crank arm arranged to engage said lever and a cam on the side bar arranged to engage said crank pin when the latter is shifted from normal position by said lever to thereby swing said shutter at the initial advance of the side bar to release all of the rack bars at such stage in the operation. 80 85

28. In a calculator, the combination with the rack bars and adding devices connected therewith, and stop bars for each of the rack bars, of a stop plate for each rack bar supported to swing and to move endwise, a flange on each stop plate arranged to be engaged by the stop bars of the set to swing the stop plate, each rack bar having a stop arranged to engage a portion of said flange to 90 retain the rack bar in normal position to be released therefrom by swinging of the stop plate, and a shutter arranged to engage all of the stop plates to shift them to bring said flanges out of engagement with the rack bars. 95 100

29. In a calculator, the combination with the rack bars and the adding devices connected therewith, stop bars for each of the rack bars, and a device for each set of stop bars arranged to release any stop bar that 105 is advanced, of a stop plate for each rack bar supported to swing and to move endwise, a flange on each stop plate arranged to be engaged by the stop bars of the set to swing the stop plate, each rack bar having 110 a stop arranged to engage a portion of said flange to retain the rack bar in normal position to be released therefrom upon swinging of the stop plate, a shutter arranged to swing to engage all of the stop plates to shift them to bring said flanges out of engagement with the rack bars. 115 120

30. In a calculator, the combination with the operating mechanism, of a side bar reciprocated in the normal operation of the machine, a lever pivotally carried by the side bar to swing thereon and to be moved 125 bodily thereby, a set of rack bars, a set of pinions, means connected with the side bar for causing the rack bars and pinions to engage and disengage, and a total key arranged to coöperate with the side bar and 130

also with its lever to thereby alter the timing of the engagement and disengagement of the pinions and rack bars.

31. In a calculator, the combination of 5 rack bars, a set of numeral pinions, a side bar reciprocated in the normal operation of the machine, a lever pivoted on the side bar, means connected with the side bar for causing engagement and disengagement of the 10 pinions and rack bars, a total key arranged to coöperate with the side bar and the lever to change the timing of the said engagement and disengagement of the pinions and rack bars, and a sub-total key on the 15 machine arranged to coöperate with the side bar and its said lever to further change the timing of the engagement and disengagement of the rack bars and pinions.

32. In a calculator, the combination of 20 rack bars, numeral pinions coöperating with the rack bars, a side bar reciprocated in the normal operation of the machine, a lever pivoted on the side bar, a shiftable member arranged to cause the rack bar and pinions 25 to engage and disengage, said member being normally engaged by the side bar on the latter part of its advance to cause said engagement of the pinions, said member being also engaged by the side bar at the latter part of its return movement to disengage the pinions and rack bars, a total key 30 arranged to coöperate with the side bar and the lever, said lever when shifted by the operation of the total key being arranged to cause said member to engage the pinions and rack bars at the initial part of the advance movement of the side bar, said lever being also operative to cause said member to disengage the pinions and rack bars at the initial part of the retraction of the side bar, a sub-total key 35 arranged to engage said lever whereby to cause said lever to engage and shift said member at the initial part of the advance of the side bar to engage the pinions with the rack bars, the lever thereupon disengaging the said member whereby the member is not shifted until the latter operation of the return movement of the side bar when the pinions and rack bars are disengaged by 40 said member and side bar.

33. In a calculator, the combination of 45 rack bars and numeral pinions coöperating therewith, a side bar reciprocated in the normal operation of the machine, a lever pivoted on the side bar, a member shiftable to connect and disconnect the rack bars and pinions, said member being engaged by the side bar at the latter portion of its advance 50 to effect said engagement of the pinions, and also being engaged by the side bar at the latter portion of its return movement to cause said member to disengage the pinions and rack bars, and a sub-total key arranged to engage said lever whereby to cause 55 said lever to engage and shift said member at the initial part of the advance of the side bar to engage the pinions with the rack bars, the lever thereupon disengaging the 60 said member whereby the member is not shifted until the latter operation of the return movement of the side bar when the pinions and rack bars are disengaged by said member and side bar.

34. In a calculator, the combination of

rack bars and numeral pinions coöperating with the rack bars, a side bar reciprocated in the normal operation of the machine, a lever pivoted on the side bar, a shiftable member arranged to cause the rack bar and pinions to engage and disengage, said member being normally engaged by the side bar on the latter part of its advance to cause said engagement of the pinions, said member being also engaged by the side bar at 70 the latter part of its return movement to disengage the pinions and rack bars, a total key arranged to engage the side bar and the lever, said lever when shifted by the operation of the total key being arranged to cause said member to engage the pinions and rack bars at the initial part of the advance movement of the side bar, said lever being also operative to cause said member to disengage the pinions and rack bars at the initial part of the retraction of the side bar, a sub-total key 80 arranged to engage said lever whereby to cause said lever to engage and shift said member at the initial part of the advance of the side bar to engage the pinions with the rack bars, the lever thereupon disengaging the said member whereby the member is not shifted until the latter operation of the return movement of the side bar when the pinions and rack bars are disengaged by 85 said member and side bar.

35. In a calculator, a side bar having a slot in one end, means for reciprocating the side bar, an operating shaft, an arm fast on the shaft, a pin on said arm, riding free in 100 said slot of the bar, a link pivoted by one end to said pin, an elbow lever pivoted on the side bar with one arm pivoted to said link, a spring connecting said pin with the pivot of said lever, a stop arranged to engage the other arm of the elbow lever when the side bar is advanced to break the toggle formed by the said link and lever arm and permit the spring to shift the said arm and shaft relative to the side bar, an arm loose 110 on the shaft, a dash-pot connected with the arm, and a link connecting said arm with the side bar causing the dash-pot to govern the entire return movement of the side bar.

36. In a calculator having a side bar and 115 means for reciprocating the side bar, the combination of an operating shaft, an arm fast on the shaft, a pin on said arm, a link pivoted by one end to said pin, an elbow lever pivoted on the side bar with one arm 120 pivoted to said link, a spring connecting said pin with the pivot of said lever, a stop arranged to engage the other arm of the elbow lever when the side bar is advanced to break the toggle formed by the said link and lever arm and permit the spring to shift the said arm and shaft relative to the side bar, an arm loose on the shaft, a dash-pot connected with the arm, and a link connecting 125 said arm with the side bar causing 130

the dash-pot to govern the entire return movement of the side bar.

37. In a calculator, the combination of rack bars, a set of adding pinions, a side bar that is moved back and forth and is provided with a pair of oppositely disposed abutments, a lever connected with the pinions to shift them to engage and disengage the rack bars, a link pivoted on said lever, a pin on said link engaged by said abutments alternately to swing the pinions to and from the rack bars, and a key stem arranged to engage the link to shift its pin out of range of engagement with said abutments.

38. In a calculator, the combination of rack bars, a set of adding pinions, a side bar that is moved back and forth and is provided with a pair of oppositely disposed abutments, an upright lever connected with the pinions arranged to shift them to engage and disengage the rack bars, a link pivoted to said lever, a pin on said link arranged to alternately engage said abutments whereby the side bar will move the pinions to and from the rack bars, an upright key stem having a transversely slotted portion engaging said pin and arranged to shift the link to move its pin out of range of engagement with said abutments.

39. In a calculator, the combination with the adding and the carrying devices, of an arm pivoted on each side of the machine, a restoring bar secured at its ends to said arms and arranged to control the carrying devices, stops for the arms, springs arranged to draw the arms against the stops, a lug on each arm, a bent lever pivoted on each side of the machine and having a hook end arranged to engage the lugs respectively to hold the restoring bar in an intermediate position, a side bar on each side of the machine, a pin on each side bar arranged to engage one of the bent levers to cause their hook portions to release the arms and bar, a bar on each side of the machine pivoted to one of said arms, means for guiding said latter bars to move back and forth and also to swing, a lug on each latter bar, a stop on each of the side bars arranged to engage the latter lugs respec-

tively to advance the bars and swing the arms and restoring bar; a shaft extending across the machine, an arm on each end of said shaft, a slide on each side pivoted to one end of each latter arm and arranged to engage said pivoted bars to shift them when the shaft is swung to bring the lugs on said bars out of position for engagement with the stops on the side bar, a swinging bar on one side of the machine, a set of keys each arranged to swing the latter bar when depressed, and a link connecting the latter bar with one of said shaft levers.

40. In a calculator, the combination with the operating mechanism, of a side bar reciprocated in the normal operation of the machine, a lever pivotally carried by the side bar to swing thereon and to be moved bodily thereby, a set of rack bars, a set of pinions, means connected with the side bar for causing the rack bars and pinions to engage and disengage, and a total key arranged to coöperate with the side bar and also with its lever to thereby alter the timing of the engagement and disengagement of the pinions and rack bars, a retracting key for the key, said key being released at the intermediate part of the movement of the side bar.

41. In a calculator, the combination of rack bars, a set of numeral pinions, a side bar reciprocated in the normal operation of the machine, a lever pivoted on the side bar, means connected with the side bar for causing engagement and disengagement of the pinions and rack bars, a total key arranged to coöperate with the side bar and the lever to change the timing of the said engagement and disengagement of the pinions and rack bars, and a sub-total key on the machine arranged to coöperate with the side bar and its said lever to further change the timing of the engagement and disengagement of the rack bars and pinions, a spring to retract the said key, said key being released at the intermediate part of the advance movement of the side bar.

JASON C. LOTTERHAND.
